Primary Examiner — Marianne Pandozzi(74) *Attorney, Agent, or Firm* — Robinson IP Law, PLLC(57) **CLAIM**

The ornamental design for a tap handle, as shown and described.

DESCRIPTION

FIG. 1 is a front perspective view of a tap handle showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines in the drawing depict portions of the tap handle with touchscreen display that form no part of the claimed design.
